UNITED STATES PATENT OFFICE.

JOHN A. WILLIAMS, OF PITMAN, NEW JERSEY, AND WALTER L. WHITMAN, 2D, OF GERMANTOWN, PENNSYLVANIA.

SUPPORT FOR CONCRETE REINFORCEMENTS.

Application filed October 8, 1926. Serial No. 140,279.

Our invention relates to means for supporting reenforcement for concrete roadways and bases, floors, ceilings, or the like.

One object of our invention is to provide 5 an improved manner of temporarily supporting reenforcing members for concrete, the supporting means being so formed that it can be withdrawn before the concrete in which the reenforcement is imbedded, has 10 solidified.

Another object of our invention is to provide an improved means for supporting metal reenforcing in a given plane.

Still another object of our invention is to 15 provide an improved means for supporting layers of reenforcing material in definitely spaced superposed relation.

One form which our invention may take is shown in the accompanying drawing, where- 20 in Figure 1 is a cross sectional view of a road bed, showing our apparatus in position, ready for pouring of the concrete; Fig. 2 is a view taken on the line II—II of Fig. 1, showing a portion of the concrete in position; Fig. 3 is a view showing one of the 25 supporting members of Fig. 2, tilted to inoperative position; Fig. 4 is a plan view of a portion of the apparatus of Fig. 1, and Fig. 5 is a view, on an enlarged scale, showing 30 means whereby the supporting bar of the three figures may be mounted at different distances above the curb or side forms on which the supporting members rest.

In Fig. 1, the road bed or sub-grade upon 35 which the concrete is to be placed is represented by the numeral 6. Side forms 7, preferably of iron or steel, are provided for defining the width of the roadway. Two sheets 8 of reenforcing fabric are shown 40 mounted in position for embedment in the concrete, but it will be understood that a single sheet may be employed in some instances, and that more than two sheets may be employed, if desired. Also, the reen- 45 forcement need not necessarily be in the form of fabric. Each sheet of fabric 8 may be composed of metal rods or wire welded or otherwise secured together to form a mesh as shown more clearly in Fig. 4.

50 In the building of reinforced roadways, difficulty has been experienced in so supporting the sheets of fabric that each sheet will

lie in a given plane, and will be imbedded in the concrete to the proper depth. In some cases, the authorities have therefore 55 required that a layer of concrete of definite thickness be placed between the forms, over a given distance, that a sheet of fabric then be placed on this previously poured concrete and that additional concrete be then poured 60 over the fabric. This has necessitated shifting the concrete mixing apparatus and materials back and forth along a given stretch of roadway several times, depending upon the number of layers of concrete and fabric 65 desired.

By our arrangement, the reenforcement is so accurately supported that the concrete can be poured to the proper thickness, in the first instance, thus rendering it possible to 70 simply move the concrete mixing apparatus and the materials along the stretch of roadway which is to be formed and rendering unnecessary the shifting back and forth of the apparatus to pour successive layers. 75

Another advantage present in our device resides in the fact that the members 7, which may represent either the ordinary side forms or curbing, serve as a fixed gage by means of which the plane of the fabric is accurately 80 determined, whereas, in prior practice, the fabric supports have rested upon an uneven sub-grade or road bed.

The fabric-supporting structure comprises 85 a bar 9 which is generally of tubular form and normally rests upon the members 7. A series of bolt-like members 10 extend through holes that are formed in the bar 9 and are provided at their lower ends with hook portion 11 that engage the fabric 90 sheets 8. The members 10 are threaded, so that by turning the nuts 12, the fabric can be adjusted in a vertical direction. The handle 13 of spring-like material is secured to one or both ends of the bars 9. These 95 handles have their outer ends turned slightly inward so that they can be sprung beneath the upper flanges of the side forms 7 and thus prevent tilting of the fabric supports under the weight of the fabric and the concrete while being poured. 100

When it is desired to remove the supports, the handles 13 are sprung upward from beneath the flanges of the side forms and the

bar 9 rocked toward the position shown in Fig. 3, thus permitting removal of the fabric-supporting structure. It will be understood that this removal will take place before the concrete has completely set.

In Fig. 5, we show a plate or block 14 of eccentric form. One of these blocks may be mounted upon each end of the bar 9. The blocks 14, when lying in the position shown in Fig. 5, rest upon the side forms 7, thus holding the bar in elevated position, and causing imbedment of the fabric sheets at higher planes in the concrete. This arrangement, in combination with the adjustment of the nuts 12, will permit the convenient positioning of one or more sheets of fabric at any desired height relative to the road bed. When the position of the blocks 14 is reversed, the bar 9, will, of course, be disposed in a lower position than that shown in Fig. 5. The handle 13^a is shown as extending through the bar 9 and detachably held in place therein by a nut 15, so that the blocks 14 can be readily removed and replaced, as desired.

We claim as our invention:—

1. Means for supporting concrete reinforcement, comprising a plurality of rotatably mounted bars, members depending from each of said bars, and reinforcement-supporting hooks on each of said members, the said hooks all extending in the same general direction and transversely of the bar.

2. Means for supporting concrete reinforcement, comprising a bar having rocking surfaces curved about its longitudinal axis, and reinforcement supporting members depending from said bar and extending transversely thereof.

3. Means for supporting concrete reinforcement, comprising a bar, fabric supporting members extending to a plane beneath said bar, and eccentrically formed blocks

loosely connected to each end of said bar

4. Means for supporting concrete reinforcement, comprising a bar adapted to be supported on the side forms of a roadway, means depending from said bar for supporting the reinforcement, and a yieldable member secured to said bar in position to extend beneath one of said forms.

5. Means for supporting concrete reinforcement, comprising a supporting member, a hook member depending therefrom in position to engage reinforcement disposed in a plane below the supporting member, and means permitting rotative movement of said hook member about an axis parallel to the said plane, to effect disengagement thereof from the reinforcement.

6. The combination with side forms for roadways and the like, of means for supporting reinforcement between said forms, comprising a hook-supporting structure carried by said forms, hook members depending from said structure, and means permitting rotative movement of said hook members about axes parallel to the plane in which the reinforcement lies.

7. Means for supporting concrete reinforcement comprising a supporting member, a hook depending therefrom in position to lie beneath the fabric when the supporting member is in one rotative position, means permitting rotative movement of the said member about an axis parallel to the plane of the fabric, and means for preventing rotative movement of said member to inoperative position under the weight of the reinforcement and the concrete.

In testimony whereof we, the said JOHN A. WILLIAMS and WALTER L. WHITMAN, 2d, have hereunto set our hands.

JOHN A. WILLIAMS.
WALTER L. WHITMAN, 2d.
